United States Patent Office

Des. 207,752
Patented May 23, 1967

207,752

COOLING TOWER OR SIMILAR ARTICLE

Torsten S. Carlson, Des Plaines, and John W. Linehan, Jr., Park Ridge, Ill., assignors to Enthalpy Products Corporation, Park Ridge, Ill., a corporation of Illinois

Filed May 27, 1966, Ser. No. 2,452

Term of patent 14 years

(Cl. D62—4)

FIGURE 1 is a side elevational view of a cooling tower, or similar article, showing my new design;

FIGURE 2 is a horizontal cross-sectional view showing the cooling tower on a reduced scale as seen along lines II—II of FIGURE 1;

FIGURE 3 is a top plan view of the cooling tower of FIGURE 1 on a reduced scale.

We claim:

The ornamental design for a cooling tower or similar article, as shown.
